ILLUMINATED DISPLAY

Frank W. Broderick, New Brighton, N. Y., assignor to Reynolds Metals Company, Richmond, Va., a corporation of Delaware

Application June 18, 1940, Serial No. 341,082

2 Claims. (Cl. 40—133)

This invention relates to an improved collapsible or knockdown display formed cheaply and economically of cardboard and metal foil stock, and having different day and night display effects and which is particularly adapted to provide when illuminated, a subsidiary "phantom" message in addition to a major sales message, and the present invention is to be regarded as an improvement of the class of illuminated signs described and claimed in Belden U. S. Patent No. 2,086,893, issued July 13, 1937, Sunderhauf U. S. Patent No. 2,148,179, issued February 21, 1939, and Sunderhauf U. S. Patent No. 2,195,977, issued April 2, 1940.

Heretofore, various illuminated displays have been suggested which by means of various translucent screens manufactured of glass or paper or the like, have been adapted to give varying effects including "phantom" effects under different conditions of illumination. Certain of the displays incorporated breakable glass parts, others were not attractive or attention compelling, and still others were extremely difficult to fabricate or to ship because they were not flat folding.

Therefore, it is an object of my invention to die-cut and die-score preferably metal foil covered cardboard into two simple parts and to add thereto a translucent screen, so that these elements can be easily and economically factory-joined together, into a flat, collapsible or knockdown display and which may be easily assembled into an upright display position for counter or window display use.

It is a further object of my invention to provide a cheap and economical day and night display having a major sales message which is readable whether the display is illuminated or not, and also having a subsidiary "phantom" sales message which is rearwardly projected upon a translucent screen through stenciled openings.

It is still a further object of my invention to manufacture flat, collapsible displays of this class in large quantities economically, and in such fashion that when assembled in upright display position, the displays are strong and stable and attractive.

It is still a further object of my invention to provide such displays formed from a main foil covered cardboard body member, die-cut and die-scored by machine methods and simply add thereto a simple translucent screen member and an outer panel member therefor, making three simple members only for factory assembly, so

far as the display itself is concerned, not including electrical adjuncts.

These and various other objects and advantages will be readily understood from the following description taken in connection with the accompanying drawing of a preferred embodiment of the invention in which modifications may be made without departing from the scope of the appended claims.

In the drawing:

Fig. 1 is a plan view of a die-scored, die-cut stenciled main body member formed of an integral piece of stock;

Fig. 2 is a plan view of a translucent screen having imprinted thereupon, a major sales message, in this instance illustrated as the number "1940";

Fig. 3 is a plan view of a panel member adapted to be mounted over the translucent screen illustrated in Fig. 2;

Fig. 4 is a fragmentary cross section taken on the line 4—4 of Fig. 1;

Fig. 5 represents the assembled parts in upright position and illuminated of a display embodying my invention;

Fig. 6 is a cross section taken on the line 6—6 of Fig. 5;

Fig. 7 is a cross section taken on the line 7—7 of Fig. 5;

Fig. 8 is an enlarged fragmentary section partly broken away, taken on the line 8—8 of Fig. 5.

In these figures, a day and night display 10 will be formed with a main body portion 12 which latter will ordinarily be die-cut and die-scored from stiff cardboard or like paper or other stock in such fashion as to provide a main display panel 14, side panels 16, bottom panel 18, and rear panel 20, and these parts will normally be integrally connected one to another having score lines 22 as indicated therebetween permitting the parts to be folded flat as indicated in Fig. 1 or assembled in upright position as indicated in Fig. 5.

As specifically indicated in Fig. 8, main display panel 14 so far as the body member 12 is concerned, will be of reduced thickness, as indicated at 24.

Main panel member 14 will have stenciled therein indicia for example, in the form of, a major display message, for example, the number "1940" identified as 23, and further indicia in the form of "phantom" sales message indicated in the illustrative figures as "ADV" and identified as 25.

A translucent screen 26 formed of glassine or

translucent paper or the like is provided, which is approximately similar in size to display panel 14 and which also has provided thereupon preferably by printing on its exterior side, the major sales message "1940", indicated as 28 and also, if desired, a contrasting colored background 30. The number "1940" on the translucent screen conforms in size and is in registry with the number "1940" upon panel 14.

Translucent screen 26 ordinarily will be adhesively mounted upon display panel member 14 of the main body portion 12, with the main sales messages on each of the parts in registry, but so that a portion of the translucent screen covers and screens that subsidiary sales message "ADV" (25). A suitable panel member 31 will normally be mounted adhesively marginally of the translucent screen member 26, as indicated.

Suitable slot members 32 and corresponding projecting members 34 will be provided for the assemblage of the display into a substantially box-like closed casing and also suitable die-cut support means indicated generally as 36 will be provided for the illuminating means indicated generally as 38, which in this instance, is illustrated as an electrical light bulb 40 with a conventional socket member 42. A flasher mechanism (not illustrated) will ordinarily be employed with the illuminating means 38 thereby giving intermittent illumination.

Main body portion 12, except for the outer side of display panel 14, will normally be covered inside and out with a thin layer of aluminum foil identified as 44, thereby giving high reflectivity of light to the interior of the casing and affording fire and water resistant qualities to a major portion of the display.

By this disposition of parts, it will be observed that when the display is not illuminated, and when there is sufficient exterior light upon the display for normal reading, that the major sales message, namely, the number "1940" is visible upon the exterior of the translucent screen as is also the contrasting background 30 (or other desired message). However, if the display is intermittently illuminated during the day time by a flasher mechanism, then the "phantom" message "ADV" is intermittently visible in illuminated form by means of the passage of reflected light through the stencil openings in display panel 12. The message "1940" will also be similarly illuminated. For even distribution of light, light rays passing through the stencils should be reflected properly.

By this means many striking advertising messages may be attractively and interestingly presented to the public. For example, the translucent screen may have imprinted thereupon, the picture of an airplane or other interesting artistic commercial representation and periodically the display may have a "phantom" subsidiary sales message flashed upon the translucent screen, giving, for instance, the name of the commercial sponsor. If desired, colored reflected light may be projected through the stencils.

It will be recognized that the arrangement of parts above described may be provided cheaply and economically by modern production methods

and that various modifications therein will occur to those skilled in the art. Accordingly, it will be realized that the essence of my invention comprises a collapsible, knockdown display formed preferably from metal foil covered stock, in which preferably three simple parts are joined together to give night and day display effects which include a main sales message and a periodic subsidiary or "phantom" sales message. It will be further recognized that if desired, two light sources might be employed with a dividing wall therebetween in such fashion that the subsidiary "phantom" sales message is periodically illuminated while at the same time, the main sales message is constantly illuminated.

Accordingly, the scope of my invention is fully defined in the appended claims, it being realized that the above description is merely for illustrative purposes and is not to be taken as limiting my invention.

I claim:

1. A die-cut and die-scored collapsible, illuminable display having day and night display values, formed substantially of cardboard or the like and including a flat-foldable casing member formed of one piece of stock, a main display panel forming a part thereof and being of reduced thickness with respect to the rest of the casing member, means for interior illumination of said casing member, indicia stencilled through said display panel, translucent screen means overlying said display panel and covering said stencilled indicia, and a cardboard framing member overlying said screen means and said display panel at the margins thereof, said framing member being of sufficient thickness so that when its thickness is added to the thickness of the display panel, the combined resultant thickness of the two members is substantially equivalent to the thickness of the remaining portions of the casing member.
2. A die-cut and die-scored collapsible, illuminable display having day and night display values formed substantially of cardboard or the like and including a flat-foldable casing member formed of one piece of stock, a main display panel forming a part thereof and being of reduced thickness with respect to the rest of the casing member, means for interior illumination of said casing member, indicia stencilled through said display panel, translucent screen means overlying said display panel and covering said stencilled indicia, a cardboard framing member overlying said screen means and said display panel at the margins thereof, said framing member being of sufficient thickness so that when its thickness is added to the thickness of the display panel, the combined resultant thickness of the two members is substantially equivalent to the thickness of the remaining portions of the casing member, and a highly light reflective lining associated with the interior of said casing and cooperating with said illumination source whereby reflective light is projected through said stencilled openings and said translucent screen to create visible indicia on the exterior of the latter.

FRANK W. BRODERICK.
